(57) **CLAIM**

The ornamental design for a musical instrument pedal, as shown and described.

DESCRIPTION

FIG. 1 is a perspective view of a musical instrument pedal showing a first embodiment of our new design;

FIG. 2 is a top plan view thereof;

FIG. 3 is a side elevational view of one side thereof;

FIG. 4 is a side elevational view of the opposite side thereof;

FIG. 5 is an end elevational view thereof viewed from the top side of FIG. 2;

FIG. 6 is an end elevational view thereof viewed from the bottom side of FIG. 2;

FIG. 7 is a perspective view of a musical instrument pedal showing a second embodiment of our new design;

FIG. 8 is a top plan view thereof;

FIG. 9 is a side elevational view of one side thereof;

FIG. 10 is a side elevational view of the opposite side thereof;

FIG. 11 is an end elevational view thereof viewed from the top side of FIG. 8; and,

FIG. 12 is an end elevational view thereof viewed from the bottom side of FIG. 8.

The broken line showings form no part of the claimed design.
